UNITED STATES PATENT OFFICE.

THEODORE VARNEY, OF PITTSBURGH, PENNSYLVANIA, ASSIGNOR TO WESTINGHOUSE ELECTRIC AND MANUFACTURING COMPANY, A CORPORATION OF PENNSYLVANIA.

CIRCUIT-CONTROLLER.

1,124,678.

Specification of Letters Patent.

Patented Jan. 12, 1915

Application filed February 1, 1912. Serial No. 674,797.

To all whom it may concern:

Be it known that I, THEODORE VARNEY, a citizen of the United States, and a resident of Pittsburgh, in the county of Allegheny and State of Pennsylvania, have invented a new and useful Improvement in Circuit-Controllers, of which the following is a specification.

My invention relates to circuit controllers for dynamo-electric machines, and it has special reference to so-called auto-starters that are provided with a neutral position intermediate a starting position and a running position, and are adapted for use in so starting induction motors that an excessive rush of current is prevented when the motors are first connected to the system.

The object of my invention is to provide a device of the above-indicated character which shall be simple and durable in construction, effective and reliable in operation, and that shall embody adequate means for effecting the circuit closure in both operating positions with a quick movement.

According to my invention, I provide a device of the above-mentioned general class which is normally biased to its neutral position and is provided with means for preventing an improper order of operation and for necessitating a quick movement in throwing the device from its starting to its running position, and one that is also provided with means having dependence upon the degree of movement of the operating handle for closing the coöperating contact members in either operating position with a quick movement of predetermined rapidity, irrespective of the speed with which the operating handle is moved.

My invention is illustrated in the accompanying drawings in which—

Figure 1 and Fig. 2 are, respectively, an end view, partially in elevation and partially in section, and a similar side view, of a portion of a device constructed in accordance with my invention, certain parts being omitted or broken away for the sake of clearness. Fig. 3 is a detail view of the operating handle and its accessories. Fig. 4 is a plan view of a portion of the operating mechanism, and Figs. 5, 6 and 7 are views, partially in section and partially in elevation, taken, respectively, along the lines V—V, VI—VI and VII—VII of Fig. 2.

Referring to the drawings, the device 1

herein shown comprises a plurality of sets 2 and 3 of stationary contact members 4 and coöperating movable contact members 5, inclosing casings 6 and 6^a, an operating mechanism 7, restraining means 8, releasing means 9, and a dog 10, the purpose of which will be hereinafter set forth.

The stationary contact terminals 4 and the movable contact terminals 5 may be of any well-known construction, although I prefer those of the butt contact type, the movable members of which are resiliently supported in the usual manner by suitable springs 11. The stationary contact terminals 4 are arranged in a plurality of rows and are secured to a supporting base or plate 12 which is suspended from ribs 13 provided in an upper casing 6^a by bolts 14. The movable contact members 5 are also arranged in rows to coöperate with the stationary contact terminals 4, said movable members 5 being suitably mounted on cross bars 15 and 16 in the usual manner. The bars 15 and 16 are respectively attached to rods 17 and 18 which project upwardly to the operating mechanism 7, through openings 19 in the supporting base 12. The several movable contact terminals 5 are electrically connected to stationary terminal members 20 by flexible conducting members 21 and are immersed in oil.

The arrangement of the parts is such that the coöperating contact members of set 2 are closed in the starting position, and, on account of the heavy currents which flow during the starting operation, the contact members of set 2 are of larger size than those which constitute set 3 in order to prevent excessive heating.

The operating mechanism 7 comprises an actuating shaft 25, an operating handle 26, supporting arms 27 and 28, a coil spring 29, a yoke or intermediate member 30; and a rod 31 that is rigidly associated with the operating shaft 25.

The supporting arms 27 and 28 are of like construction and are independently and loosely mounted upon the actuating shaft 25 and adapted to pivotally support the rods 17 and 18 upon pins 32. Each supporting arm is provided also with an extended portion 33 which serves as a stop and rests against one of the ribs 13 of the casing 6^a when the device is in its neutral position. A projecting member 34 forms an integral part of each of the supporting

2
arms 27 and 28, and is provided with an inclined under surface 35, for a purpose to be hereinafter pointed out.

The releasing means 9 constitutes a cam member which is fixed to the shaft 25 and is provided with symmetrically located cam surfaces 36 and 37, and with an upwardly projecting trigger member 38 which is adapted to engage the dog 10 in a manner to be hereinafter described.

The outer end of the rod 31 is secured to the cam member 9, while its inner end is associated with a member 40 that is fixed with respect to the shaft 25, the rod 31 being disposed directly below, and parallel to, the axis thereof. The spring 29 surrounds the shaft 25 and its opposite ends 41 and 42 are disposed on the respective sides of the rod 31 and in engagement therewith.

The intermediate or yoke member 30 comprises a main body portion 43 of partially cylindrical contour and a longitudinal extension or projecting portion 44, said member 30 being suspended below the actuating shaft 25 and the rod 31 by means of a plurality of upwardly projecting bearing members 45, 46 and 47 which form integral parts of the intermediate member 30 and loosely surround the shaft 25. The end bearing member 45 is located between the supporting arms 27 and 28 and a collar 48 which is pinned to the shaft 25; the opposite end bearing member 47 surrounds the shaft 25 between the cam member 9 and the outer end 42 of the spring 29, while the central bearing member 46 is located intermediate the supporting arms 27 and 28 and the member 40. The body portion 43 of the yoke member 30 is provided with a longitudinally disposed web or rib 49 which is located directly below the rod 31 and in proximity thereto. The ends of the spring 29 project into cooperative engagement with the respective sides thereof for a purpose to be set forth.

The outer bearing member 47 is provided with an elongated curved slot 50, through which rod 31 projects, in order to permit relative movement between said rod 31 and intermediate member 30. Furthermore, the opposite upper edges 51 of the bearing member 47 are provided with removable plates 52 of particularly durable material, and which embody catches 53 and 53^a. The extension 44 of the intermediate member 30 projects beneath the supporting arms 27 and 28, and is provided with inclined sides 54 which are adapted to engage the inclined surfaces 55 and 35 of the supporting arms 27 and 28 during the operation of the device.

The releasing means 8 comprises a plurality of latches 57 and 58 which are pivotally mounted upon the lugs 59 and 60, forming a part of the inclosing casing 6^a, and are disposed in vertical alignment with

the catches 53 and 53^a and the cam surfaces 36 and 37. The latches 57 and 58 are of like construction and each is provided with a pivotally mounted roller 62 which is adapted to be co-operatively engaged by one of the surfaces 36 and 37 of the cam member 9, and with a portion 63 which is adapted to co-operate with one of the catches 53 and 53^a in order to restrain the movement of the intermediate member 30 until finally released through the agency of the cam member 9 and a roller 62. The latches referred to are maintained in their normal operating positions by a spring 64 which is connected between them.

The dog 10 is pivotally mounted within the casing 6^a upon a pin 70, and comprises a hooked arm 71 which is partially counterbalanced by a weighted member 72. The under surface of the arm 71 is provided with a notch 73, the right-hand side of which is vertically disposed, and said notch 73 is adapted to receive the upper end of the trigger member 38, whereby an initial movement in a clockwise direction, that is, into the running position of the device, is prevented. Furthermore, the end of the arm 71 is provided with a downwardly projecting portion 74, having an inclined cam surface 75.

By reason of the arrangement of the parts just referred to and the peculiar contour of the dog 10, movement of the operating handle 26 in a counter clockwise direction, is permitted, during which movement the dog 10 is forced upwardly until the trigger member 38 is freed from the projecting portion 75, after which it drops into its normal position. If the operating handle 26 is moved slowly in a clockwise direction, the dog 10 is first raised during the engagement of the trigger member 38 and the inclined cam surface 75 thereof, after which the dog 10 drops into its normal position and restrains further movement of the operating handle 26 in a clockwise direction. On the contrary, if the operating handle 26 be moved quickly, the dog 10 is thrown upwardly, and the trigger member 38 is permitted to pass the recess 73 before the dog 10 descends into its normal position. Thus, the operating handle 26 can be moved through its neutral position in a clockwise direction only by a rapid movement and an operator is thereby compelled to throw the device quickly from its starting to its running position.

The operating handle 26 is rigidly fastened to the operating shaft 25, and, as hereinbefore intimated, is adapted to be moved into either side of its normal neutral position into the starting and running positions. By reason of springs 11 which support the movable contact members 5, as well as the weight of the component parts of the op-

erating mechanism, the device is biased to its neutral position.

Within the handle 26, a rod 76 is movably disposed, the upper end thereof being provided with a button 77 which projects through a grip 78 and the lower end being provided with a locking member 79 which projects through an opening 80 in the handle 26 and cooperatively engages a position-accentuating plate or member 81. A spring 82 surrounds the rod 76 between the button 77 and a portion 83 of the handle 26, and tends to hold it in its upper position. The plate 81 is secured to the casing 6^a in a suitable manner and is provided with an upper curved portion 84, having notches 85 and 86 respectively located in the middle of the portion 84 and to the right thereof, in order to receive the locking member 79, as shown in Fig. 3, whereby the handle 26 may be restrained in its neutral and its running position. No notch is provided to the left of the central notch 85, and, hence, the operating handle 26 cannot be left in its starting position, but, if released, will immediately return to its central position.

Assuming the parts of the device to occupy the positions shown in the drawing, the device is locked in its neutral position and can only be moved therefrom by releasing the handle 26 from the position-accentuating plate 81 by depressing the button 77. Having released the handle 26 in the manner mentioned, the operator may throw the handle to the left into the starting position, but is prevented from throwing it into its running position by the dog 10, as hereinbefore explained. During the first part of the movement into the starting position, the yoke or intermediate member 30 is rotated slightly in a counter clockwise direction by reason of the cooperative action of the rod 31 which is rigidly associated with the shaft 25 and the spring 29, as will be readily understood. The catch 53^a is thus brought into engagement with the latch 58 and further movement thereof is thereby prevented. During this movement, the extension member 44 of the intermediate member 30 is also brought into engagement with the inclined surface 55 of the supporting arm 28. As the operator continues to move the handle toward the starting position, energy is stored in the spring 29 because of the relative movement that is permitted between the shaft 25 and the restrained intermediate member 30 by reason of the slot 50. When the handle 26 has been moved a predetermined amount from its neutral position, the cam surface 37 of the cam member 9 engages the roller 62 that is associated with the latch 58, and said latch is thus rotated out of engagement with the catch 53^a, whereby the energy of the spring 29 causes the intermediate member 30 to be

suddenly rotated in a counter-clockwise direction at a predetermined speed which is dependent upon the characteristics of the spring. Inasmuch as the intermediate member 30 already engaged the supporting arm 28 previous to the release of the spring 29, it is evident that, when the intermediate member 30 is actuated, it carries with it the supporting arm 28 and also the movable contact terminals 5 that are suspended by 75 the rod 18. Thus, the cooperating contact members comprising set 2 are brought into engagement with a snap movement, and the circuit closure in the starting position is effected with predetermined rapidity. It is 80 evident that the speed of closing the contact members is dependent upon the spring 29 and independent of the speed with which the operator moves the operating handle 26.

In throwing the device into its running 85 position, the operator is compelled to do so with a quick movement by reason of the dog 10, as already explained, and hence a quick break of the cooperating contact members 4 and 5 is obtained. Immediately upon moving the handle 26 from its starting position, the movable parts of the device resume their neutral position through the action of the contact-bearing springs 11 and the weight 90 of the parts referred to, after which the 95 movable contact members 5 that are associated with set 3, are closed with a predetermined speed through the same cycle of operation, as hereinbefore set forth, it not being deemed necessary to describe the operation, on account of its similarity to that just recited in detail. It is evident, therefore, that the circuit closure of the device in its running position is also effected at a predetermined speed that is independent of the 100 operator's actions. The operating mechanism may be held in its running position until the button 77 is depressed by the operator, as the projecting portion 79 then engages the notch 86 in the position-accentuating plate 81, after which it will return to its normal neutral position.

Although I have shown and described a circuit-closing device, or so-called auto starter, that embodies specific structural details and a particular arrangement and location of parts, it will be understood that various modifications may be effected from what is herein set forth without departing from the spirit and scope of my invention, 115 and I desire that only such limitations shall be imposed as are indicated in the appended claims.

I claim as my invention:

1. In a circuit controller, the combination 125 with a plurality of sets of cooperating stationary and movable contact members, an operating shaft and mechanism therefor, and means for preventing an improper order of operation, of means embodying a spring 130

disposed around said shaft for effecting a quick closure of each set of coöperating contact members.

2. In a circuit controller, the combination with a plurality of sets of coöperating stationary and movable contact members, an operating shaft associated with said members, a mechanism for operating the same, and means for preventing an improper order of operation, of means embodying a single torsional spring associated with said operating mechanism and disposed around said shaft for effecting a predetermined quick closure of each set of coöperating contact members, irrespective of the speed of operation.

3. In a circuit controller, the combination with a switching device and a handle having a neutral position between its starting position and its running position, an operating mechanism comprising said handle, means for preventing the operation of said device in an improper order, and means for compelling a quick operation in throwing said device and handle from its starting to its running position, of means for effecting a quick circuit closure in both operating positions.

4. In a circuit controller, the combination with a switching device and a handle having a neutral position between its starting position and its running position, an operating mechanism comprising said handle, means for preventing the operation of said device in an improper order, and means for compelling a quick operation in throwing said device and handle from its starting to its running position, of means embodying a single spring for effecting the circuit closures in both operating positions with a snap movement.

5. In a circuit controller, the combination with a switching device and a handle having a neutral position between its starting position and its running position, an operating mechanism comprising said handle, means for preventing the operation of said device in an improper order, and means for compelling a quick operation in throwing said device and handle from its starting to its running position, of means associated with said operating mechanism and dependent upon the movement thereof for effecting circuit closures at predetermined speeds, irrespective of the speed of operation.

6. In an auto-starter, the combination with a double-throw switching device having a normal neutral position, a mechanism biased to the neutral position for operating said device, and means for preventing the closure of said device in one direction except through a closure in the opposite direction and for necessitating a quick movement

from one operating position to the other, of a spring-actuated mechanism associated with said operating mechanism for making the circuit connections in both operating positions with a snap movement.

7. In an auto-starter, the combination with a double-throw switching device biased to a neutral position, means for preventing the closure of said device in an improper order and for necessitating a quick movement from the starting position to the running position, an actuating shaft, a spring surrounding the same, and means for storing energy in said spring when said shaft is rotatively moved in either direction, of means dependent upon the amount of rotative movement for causing said spring to effect a closure of said switching device with a quick movement.

8. In an auto-starter, the combination with a plurality of sets of coöperating stationary and movable contact members, an actuating shaft, a supporting member loosely mounted on such shaft and carrying said movable contact members, and an intermediate member loosely mounted thereon and adapted to engage said supporting member, of a spring surrounding said shaft, means for associating the opposite ends of said spring with said shaft and said intermediate member in either direction of shaft movement, means for restraining said intermediate member, and means for releasing said restraining means, whereby the spring is adapted to close one set of coöperating contact members through the agency of said intermediate member and said supporting member.

9. In an auto-starter, the combination with two sets of coöperating stationary and movable contact members normally held out of engagement, an actuating shaft, means for suspending said movable contact members therefrom, an operating handle secured thereto, a coil spring surrounding said shaft and having one end associated therewith, an intermediate member loosely mounted on said shaft and associated with the other end of said spring, latches to restrain the movement of said intermediate member, a cam fixed to said shaft and adapted to release said latches under predetermined conditions, whereby either set of coöperating contact members is closed with a quick movement according to the direction of movement of said operating handle.

In testimony whereof, I have hereunto subscribed my name this 18th day of Jan. 1912.

THEODORE VARNEY.
